US0D1064641S

(12) **United States Design Patent** (10) **Patent No.:** **US D1,064,641 S**
(45) **Date of Patent:** **** Mar. 4, 2025**

(54) **SPROCKET FOR PET WASTE CARTRIDGE**

(71) Applicant: **BRILLIANT PET 2 LLC**, Chicago, IL (US)

(72) Inventors: **Alan Jay Cook**, Chicago, IL (US); **Kristin W. Grube**, Bloomington, IN (US); **Kevin John Augustyniak**, Elma, NY (US)

(73) Assignee: **BRILLIANT PET 2 LLC**, Chicago, IL (US)

(**) Term: **15 Years**

(21) Appl. No.: **29/832,505**

(22) Filed: **Mar. 28, 2022**

Related U.S. Application Data

(63) Continuation-in-part of application No. 16/698,559, filed on Nov. 27, 2019, which is a continuation-in-part of application No. 16/513,000, filed on Jul. 16, 2019, now Pat. No. 12,010,974, which is a continuation of application No.

(57) **CLAIM**

The ornamental design for a sprocket for pet waste cartridge, as shown and described.

DESCRIPTION

FIG. 1 is a front perspective view of the sprocket for pet waste cartridge;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a sectional view taken along reference lines 8 shown in FIG. 2;

FIG. 9 is a sectional view taken along reference lines 9 shown in FIG. 4;

FIG. 10 is a top perspective view thereof; and,

FIG. 11 is a bottom perspective view.
